DISK CULTIVATOR.

No. 530,932.

Patented Dec. 18, 1894.

UNITED STATES PATENT OFFICE.

HARRY E. DODSON, OF SPRINGFIELD, OHIO, ASSIGNOR TO THE P. P. MAST & COMPANY, OF SAME PLACE.

DISK CULTIVATOR.

SPECIFICATION forming part of Letters Patent No. 530,932, dated December 18, 1894.

Application filed April 6, 1894. Serial No. 506,588. (No model.)

To all whom it may concern:

Be it known that I, HARRY E. DODSON, a citizen of the United States, residing at Springfield, in the county of Clark and State of Ohio, have invented certain new and useful Improvements in Disk Cultivators, of which the following is a specification, reference being had therein to the accompanying drawings.

This invention relates to certain new and useful improvements in cultivators and the peculiar novel features are hereinafter fully described and particularly pointed out in the claims.

In the accompanying drawings on which like reference letters indicate corresponding parts: Figure 1, is a plan view of my improved cultivator; Fig. 2, a detail view of one of the axle connections; Fig. 3, a sectional view of the same in detail; Fig. 4, a detail view showing a part of the main frame and the connection of the axle; Fig. 5, a rear elevation of the machine as shown in Fig. 1, with the seat omitted; Fig. 6, a detail side elevation and sectional view of the fixed and movable blocks and other adjacent parts; Fig. 7, a transverse sectional view of the same on the line $x-x$ of Fig. 6; and Fig. 8, a longitudinal sectional view of the same parts on the line $y-y$ of Fig. 7.

The letter A designates the two branches of the pole or tongue which, near their forward ends, unite. A doubletree B is carried by the pole and also a cross bar C. The branches A of the pole are secured to the axle, which consists of bars D D, bolted at their ends to a casting E. This casting has a stout depending part F, curved in cross section, to stiffen it, as seen in Figs. 2, and 4. The stud G is cast on the lower end of the part F and a hole is formed in the flange H of the casting E. The wheel spindle I is secured to a casting J which receives the stud G. A stud K is on the casting J and fits up through an opening in the flange H. The casting J further carries a lug L, which is bolted to an arm S. Thus the casting J, in effect, forms a part of the spindle or axle and is swiveled or pivotally mounted on a vertical axis. The arms M, shown partly in Fig. 1, are interconnected by a cross bar O to which is attached at P a

hand lever Q, the pivot R of the hand lever extending down over the axle and being shown in Figs. 1 and 5. Thus by taking hold of the hand lever Q when the machine is being used as a walking cultivator, the wheels 55 can be deflected in or out so as to move the frame of the machine laterally and carry the disk beams with it so as to deflect them to agree with the irregularities of the rows. Foot-bars S are attached in any suitable manner to the arms M and when the machine is being used as a riding cultivator and the driver is mounted on the seat T he can move the machine laterally by placing his foot on these bars S, for the same purpose. 65

A stout beam U is secured upon the branches of the pole, and carries bearings V, for the rock-shaft W. One of the bearings V has a toothed segment V' engaged by the spring detent X of the lever Y mounted on the rock-shaft. This shaft carries arms Z which have attached to them spring-lifting rods a, such rods at their lower ends suitably connecting with disk-beams, whereby the latter may be raised and the disks suspended above the 75 ground, whereby they may also be pressed downward and the disks made to take into the soil.

Referring again to the beam U, it carries a band b which supports the seat bars c, the 80 forward ends of such bars being bolted to the branches of the pole, as seen at d in Fig. 1.

Referring now to the disk beams it will be seen that they consist each of two bars e, e, spread apart at their forward ends where 85 they are connected to a block f, which is bolted to the cross-piece C. Slots g permit the forward ends of these beams to be shifted laterally. Any other suitable way of connecting the forward ends of the disk beams will 90 answer the purpose. The rear portions of the bars e run substantially parallel and are let into the fixed bearing block h, and held to it by a cap i, which fits over the bars, and by a bolt and nut. In order to interconnect the 95 rear ends of these disk beams, I provide a yoke or arch k, which connects with the fixed bearing blocks h. These blocks have forward extensions l, as seen in Figs. 1 and 8, and the arch or yoke k is fitted into recesses in the 100

ends of these extensions and held by screws *m*. The arch or yoke has a series of holes *o*, as seen in Fig. 5, so that the distance between the rear ends of the disk beams may be adjusted to agree with the distance between their forward ends where they are connected with the cross bar *C*. Thus the cross beam *C*, the bars *e* and the arch or yoke *k*, form a rigid structure so far as lateral movements are concerned; and this structure is not only thus rigid in itself, but it is rigid laterally in its relation to the axle or main frame of the machine. Thus the remarks hereinbefore made as to directing the wheels in and out from the line of travel so as to move the disks laterally, will be further understood.

I come now to a detailed description of the means for connecting the gang of disks with this rigid beam structure. The fixed bearing blocks or plates *h* are radially serrated on their under sides, as seen at *p*, Figs. 6 and 7. Adjustable bearing blocks *q* are serrated on their upper faces to match the serrations *p*. These blocks *q* are curved out on their under sides in a transverse direction, as seen in Fig. 7, and have longitudinal serrations, as shown at *r* in that figure. Rolling bearing blocks *s* are correspondingly curved and serrated to match the adjustable bearing blocks *q*. This curve of the rolling bearing blocks is therefore also transverse, as seen in Fig. 7. In a longitudinal direction these rolling blocks are straight on their upper faces so as to form a long flat bearing in that direction. To these rolling bearing blocks are secured the gang yokes *t*. The bolts *j*, above referred to, pass through the yokes *t*, the rolling bearing blocks *s*, the adjustable bearing blocks *q*, the fixed bearing blocks *h* and the cap *i*, and act to bind all of these parts firmly and rigidly together in any relative position in which they may have been first adjusted. The rolling bearing blocks *s* are slotted as seen at *s'* so that they may be rolled laterally about the bolts *j*. This adjustment of the rolling bearing blocks with respect to the beams and independently of them and with respect to the ground surface is to incline the shafts *u* and consequently to set the inner or the outer of the disks *v* deeper or shallower in the ground, as may be required for the work at hand. Then the long bearing of the bearing blocks *q* on the bearing blocks *s* in a longitudinal direction stoutly holds the yokes *t* against swaying backward at their lower ends as they are strained in advancing the disk-shafts and gangs forward. Then to adjust the disk shafts more or less obliquely to the line of travel, the adjustable bearing blocks *q* are rotated more or less with respect to the fixed bearing block *h*, by loosening the bolts *i*, and then tightening them again when the proper angle of the disk shafts to the line of travel is had.

Thus it will be understood that my disk gangs are carried by beams which have no

lateral adjustment except by shifting the whole body of the machine from one side to the other by properly directing the wheels; also, that the disk shafts may be tilted to and from the ground at their respective ends so that the inner or the outer disks may be adjusted deeper or shallower in respect to the ground. Further, that these shafts may be turned more or less obliquely to the line of travel.

I am aware that it is not new, in a broad sense, to turn or adjust the disk shafts more or less obliquely to the line of travel, but I have an improved construction for doing this. I am further aware that it is not now new to tilt the disk shafts with respect to the ground, but I have an improved organization and arrangement for this purpose.

At *w* are shown socket arms carried by the rolling bearing blocks, in which is mounted a shaft *w'* carrying scrapers *x'*. Fenders or guards *y'* are also sometimes used and connected to the gang beams.

Having thus fully described my invention, what I claim as new, and desire to secure by Letters Patent, is—

1. In a cultivator, the combination with a gang beam non-movable laterally and braced to prevent twisting, but adjusted up and down, of a fixed bearing block connected thereto, a rolling bearing block convexed laterally and substantially straight longitudinally, and connected with the fixed bearing block by intermediate devices, and cultivating disks whose shaft is carried by the rolling bearing block, whereby the inner or the outer of said disks may be adjusted deeper or shallower into the soil.

2. In a cultivator, the combination with a beam, a fixed bearing block and a cap engaging therewith, a rotatable bearing block, interlocking serrations between said bearing blocks, and a transverse serrated concave in the rotatable bearing block, a serrated rolling convexed bearing block fitting in said concave and matching with its serrations and slotted laterally, a bolt which binds the three bearing blocks and the fixed bearing block and cap to the beam, a yoke carried by the rolling bearing block, a shaft carried by the yoke, and cultivating disks on said shaft.

3. In a cultivator, the following instrumentalities: the main frame, supporting wheels swiveled thereto, and means to guide the wheels in and out of the line of travel, two beams attached to the forward part of said frame by a joint permitting up and down adjustment but resisting lateral movements of the beams, a cross-yoke secured to the rear ends of the beams, a fixed bearing block for each beam, and a rolling bearing block engaging with each fixed bearing block, a yoke connected to each rolling bearing block, a shaft carried by each yoke, and disks carried by each shaft, and a bolt which binds each pair of said bearing blocks together and to

their respective beams, the arrangement between the fixed bearing blocks and the rolling bearing blocks and said bolts, respectively, permitting of the rolling bearing blocks with 5 their yokes to be adjusted to raise and lower the ends of the yoke to and from the ground and at different angles to the line of draft, and the swivel connection of the supporting

wheels compensating for the lateral rigidity of the beams.

In testimony whereof I affix my signature in presence of two witnesses.

HARRY E. DODSON.
